UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

CALL-INDICATING SYSTEM.

1,280,258.

Specification of Letters Patent.

Patented Oct. 1, 1918.

Application filed November 1, 1916, Serial No. 128,874. Renewed March 13, 1918. Serial No. 222,241.

To all whom it may concern:

Be it known that I, ALBEN E. LUNDELL, a citizen of the United States, residing at New York, in the county of Bronx and 5 State of New York, have invented certain new and useful Improvements in Call-Indicating Systems, of which the following is a full, clear, concise, and exact description.

This invention relates to trunking in telephone exchange systems, and more particularly to systems in which automatic means are provided for informing a final connecting operator of the number of the wanted line.

15 It is the object of this invention to provide an improved means for informing a final connecting operator of the number of the wanted line by means of visual signals.

A feature of the invention is an arrangement by which a sequence switch rotates 20 through its cycle to send impulses in accordance with the setting of a register, which may be a manually adjusted keyboard, or some type of electromagnetically adjusted 25 switch.

A further feature of the invention is the utilization of both sides of the trunk for impulse sending, the impulses over one side of the trunk being used to operate a step-by-step switch, and the impulses over the other side being used to energize desired ones of a 30 combination of locking relays, such other side of the line being successively extended to said relays by the operation of the step-by-step switch.

The invention has been shown as applied to a telephone exchange system of the well-known semi-automatic type, but is obviously capable of arrangement for use in other systems.

It is thought that the invention will best be understood from the following detailed description, reference being had to the accompanying drawings.

45 In the drawings, Figure 1 represents the substation apparatus of a calling subscriber and an A operator's connecting cord circuit, together with a selector switch for extending the calling line to a trunk leading to a B 50 operator's position. In Fig. 2, portions of a connecting circuit at the B operator's position are shown, together with the substation line and apparatus of a called subscriber. A step-by-step switch which con-

trols the call indicating device is indicated 55 in the lower portion of Fig. 2. Fig. 3 represents the A operator's sending device and the operating circuits therefor. In Fig. 4 the relay combination controlling the lighting of the number indicating lamps is illustrated.

It is to be understood that in practice there would be only one sender per operator's position, and that this sender would be associated with the proper cord circuit by 65 means of a cord finder switch. Since this arrangement is well-known in the art, the cord finder has been omitted for the sake of simplicity, and it has been assumed that there is a sender in permanent association 70 with each cord.

When the subscriber at substation 1 desires a connection, he removes his receiver from the hook, causing the display of a line signal 2 by the operation of line relay 3 in 75 the well-known manner. The connecting operator at 0, upon observing the lighted lamp 2, inserts a plug 4 into a jack 5 associated with lamp 2, whereupon cut-off relay 6 is energized over a circuit from grounded 80 battery, winding of relay 6, sleeve contact of jack 5, sleeve of plug 4, winding of relay 7, to ground. Relay 7 is energized and completes a circuit for the power magnet 100 of the connecting cord sequence switch from 85 grounded battery, winding of power magnet 100, connecting cord sequence switch contact 101, front contact and armature of relay 7 to ground. The connecting cord sequence switch moves from position 1 into 90 position 2, under the control of its normal contact 102.

In position 2 of the connecting cord sequence switch, a circuit is completed from ground, connecting cord sequence switch 95 contact 103, sender sequence switch contact 104, winding of power magnet 105 of the sender sequence switch to grounded battery. The sender sequence switch then moves from position 1 to position 2 under the 100 control of its normal contact 106. A circuit is now completed for relay 8 from grounded battery, winding of relay 8, connecting cord sequence switch contact 107, conductor 108, armature and back contact of the upper 0' 105 counting relay, winding of stepping magnet 109, sender sequence switch contact 110, conductor 111, to ground at connecting cord

sequence switch contact 112. Relays 8 and 109 are energized in this circuit. Relay 8, at its left-hand armature and front contact, locks itself to conductor 108 through connecting cord sequence switch contact 113, and at its right-hand armature and front contact, completes a circuit from ground, through connecting cord sequence switch contact 114, for moving the connecting cord sequence switch out of position 2 into position 3.

It is to be understood that the operator at 0 has in the meantime ascertained the number of the desired line in the well-known manner. She then depressed one of the keys 115, 116, 117, etc., which control the counting relays, to cause the selector associated with her cord circuit to hunt in a section whose trunks run to the desired office. She also depressed a key in each of the sets 20 K, K'. It is assumed that the called subscriber's number is composed of only two digits for the sake of simplicity. It is obvious, however, that the system could be extended to indicate any desired number of digits.

Let us assume that the trunks running to the desired office are located in the first group of contacts of the selector, and that 30 the number of the wanted subscriber is 47. The operator will then have depressed office key 115, the fourth tens key and seventh units key.

In position 3 of the connecting cord sequence switch, a circuit is closed for updrive power magnet 118 from grounded battery, winding of magnet 118, connecting cord sequence switch contact 119, armature and front contact of relay 8 to ground. The 35 operation of the updrive magnet 118 forces a driving ribbon 120 into engagement with a constantly rotating roller 121, to move a brush set 122 upward in the well-known manner. The stepping relay 109 is intermittently shunted out over a path from the left-hand armature and front contact of relay 8, connecting cord sequence switch contact 123, conducting segments of a commutator 124 and brush 125 to ground. This 40 45 intermittently actuation of relay 109 successively operates the counting relays in the well-known manner. When the upper counting relay 0' is energized, the circuit of relay 109 is permanently opened, and when brush 125 engages the next insulating segment, the alternate path of relay 8 to ground is broken, and this relay also deenergizes. The energization of the upper counting relay 0' completes a circuit from ground, 50 55 right-hand front contact of the upper 0' counting relay, sequence switch contact 126, the winding of power magnet 105, to grounded battery, to move the sender sequence switch out of position 3 into position 60 65 4. The deenergization of relay 8 completes

a circuit from ground, right-hand armature and back contact of relay 8, connecting cord sequence switch contact 127 and winding of power magnet 100, for moving the connecting cord sequence switch out of position 3 and into position 11.

The brush set 122 hunts for an idle trunk to a B operator's position indicated at 0' in a position of the connecting cord sequence switch between positions 3 and 11, in the 75 well-known manner.

When the brush set 122 comes to rest on the terminals of an idle trunk, a circuit is completed for relay 128 from ground, winding of relay 128, sender sequence switch contact 129, conductor 111, connecting cord sequence switch contact 130, brush 131, terminal 132, lower contact of spring 133, upper left-hand winding of a repeating coil 134, and winding of relay 135 to grounded battery. Relays 128 and 135 are energized, relay 128 closing at its front contact a circuit from ground through sender sequence switch contact 136, for moving the sender sequence switch out of position 3 and into 90 position 4. Relay 135 completes a circuit from grounded battery, lamp 137, conductor 138, armature and front contact of relay 135, armature and back contact of relay 139, resistance 140 to ground. Trunk signal 137 is lighted in this circuit and informs the operator that a call is coming in over the trunk with which such signal is associated. She then depresses the key whose 95 springs are indicated at 133, 141 and 142, and maintains it depressed until the lighting of the number indicating lamps informs her of the number of the desired line.

When key 133 is operated, battery is removed from conductor 111, and relay 128 deenergizes, closing at its armature and back contact a circuit through sender sequence switch contact 143, for moving the sender sequence switch out of position 4 and into 105 position 5.

When the sender sequence switch arrives in position 5, a circuit is completed from ground, sender sequence switch contact 144, impulse sending switch contact 145, winding of power magnet 146 of an impulse sending switch, to grounded battery. This switch, when actuated, rotates through its cycle of positions without stopping until it returns to normal position. Impulses are sent over the lower trunk conductor from ground, impulse sending switch contact 147, sender sequence switch contact 148, conductor 108, connecting cord sequence switch contact 149, brush 150, terminal 151 over the lower contact of key spring 141, left-hand armature and back contact of relay 152, and the winding of relay 153, to grounded battery. Impulses are sent over the upper trunk conductor, in accordance with the setting of key sets K and K', over conductor 154, 110 115 120 125 130 135 140 145 150 155 160

sender sequence switch contact 155, conductor 111, connecting cord sequence switch contact 130, brush 131, terminal 132, upper contact of key spring 133 and wiper 156 of 5 a step-by-step switch controlled by magnet 157, to certain ones of a locking relay combination.

The embodiment shown is arranged to indicate the number of two digits only, the 10 tens lamps being indicated in the group at the right, and the units lamps being indicated in the group at the left. It is to be understood, however, that the system might 15 readily be arranged for use with any desired number of digits.

The operation of the indicating device will now be described. Assuming that the number of the called line is 47, the operator will depress key 4 of key set K and key 20 7 of key set K'. When the impulse sending switch passes from positions $1\frac{1}{2}$ to $2\frac{1}{2}$, contact 147 will be closed, completing the previously traced circuit for relay 153. Relay 153 will be energized and completes 25 a circuit from grounded battery, winding of stepping magnet 157, wiper 158 and its first contact, armature and front contact of relay 153 to ground. The operation of the switch controlled by magnet 157 will 30 cause wipers 156, 158 and 159 to be advanced into their second positions. Locking relay 160 is now connected to the upper trunk conductor through side-switch wiper 156, but is not energized since conductor 154 35 finds no ground while the impulse sending switch is passing through position 2, due to the fact that conductor 161 is not connected to contacts of key 4 in the tens group. When the impulse sending switch leaves 40 position $2\frac{1}{2}$ relay 153 is deenergized, and a circuit is completed from grounded battery, winding of stepping magnet 157, wiper 158 in its second position, armature and back contact of relay 153 to ground. The step- 45 by-step switch wipers are now moved from position 2 to position 3.

When the impulse sending switch passes from positions $3\frac{1}{2}$ to $4\frac{1}{2}$, relay 153 is again energized to advance the step-by-step switch 50 from position 3 to position 4. In this position relay 162 is connected to the upper trunk conductor over side-switch wiper 156, but is not energized since no ground is put on conductor 154 when the impulse sending switch passes through position 4. On leaving position $4\frac{1}{2}$, relay 153 is deenergized and moves the step-by-step switch into position 5.

When the impulse sending switch passes 55 from positions $5\frac{1}{2}$ to $6\frac{1}{2}$, relay 153 is again energized to move the step-by-step switch from position 5 to position 6. At this time relay 163 is connected to the upper trunk conductor, but is not energized since no 60 ground is put on conductor 154 when the

impulse sending switch passes through position 6. The step-by-step switch is moved into position 7, as previously described.

When the impulse sending switch moves through positions $7\frac{1}{2}$ to $8\frac{1}{2}$, relay 153 is 70 energized to move the step-by-step switch into position 8. At this time relay 164 is connected to the upper trunk conductor as described, but is not energized since conductor 154 finds no ground when the impulse sending switch moves through position 8. The step-by-step switch is moved into position 9 as before described.

When the impulse sending switch passes from positions $9\frac{1}{2}$ to $10\frac{1}{2}$, the step-by-step 80 switch is moved into position 10. At this time relay 165 is connected to the upper trunk conductor and is energized, since conductor 154 is grounded when the sending switch passes through position 8 over a path 85 through impulse sending switch contact 166, conductor 167, closed contact of key 7 of the set K', to ground. Relay 165 locks itself up over a path from grounded battery, winding of relay 165, its armature and 90 left-hand front contact, conductor 168, armature and front contact of relay 169, to ground. Relay 169 was energized when key spring 142 was closed, over a path from 95 grounded battery, winding of relay 169, to ground through the closed contact of key spring 142. When the sending switch leaves position $10\frac{1}{2}$ the step-by-step switch is moved into position 11, as previously described. The step-by-step switch will 100 continue to be advanced in the manner described under the control of contact 147. No more of the locking relays are energized, since conductor 154 fails to find ground when the impulse sending switch moves 105 through positions 12, 14 and 16. When the sending switch leaves position $16\frac{1}{2}$ the step-by-step switch moves into position 17.

At this time a circuit is completed for 110 relay 152 from grounded battery, winding of relay 152, conductor 170, wiper 159 and its 17th contact, to ground. The operation of relay 152 opens the circuit of relay 153 and prevents any difference in potential between the battery of repeating coil 188 and 115 the battery at the office at which relay 153 is located, from causing an undesired energization of relay 153, when the connecting cord sequence switch moves into position 16 as will be later described.

When wiper 159 arrives in position 17, the 120 circuits for lamp 4 of the tens group and lamp 7 of the units group are completed as follows, it being remembered that of the locking relays only relay 165 is energized. 125 The circuit of lamp 4 of the tens group extends from grounded battery, right-hand armature and back contact of relay 164, conductor 171, outer right-hand armature and back contact of relay 163, outer right- 130

hand armature and back contact of relay 162, lamp 4, outer right-hand armature and back contact of relay 160, to conductor 172, which is grounded through wiper 159 in its 17th position. The circuit of lamp 7 of the units group extends from grounded battery, right-hand armature and front contact of relay 165, conductor 173, inner right-hand armature and back contact of relay 174, inner right-hand armature and back contact of relay 175, lamp 7, inner armature and back contact of relay 176, to grounded conductor 172.

It is to be noted that at this time no other lamps can be lighted in the tens group, since the unactuated condition of relay 164 prevents battery being supplied to lamps 9, 7, 5, 3 and 1; the unactuated condition of relay 163 prevents lamp 8 from being lighted; the unactuated condition of relay 162 prevents lamps 6 and 2 from being lighted, and the unactuated condition of relay 160 prevents lamp 0 from being lighted.

Similarly, in the units group no other lamp than lamp 7 can be lighted, since the actuated condition of relay 165 prevents lamps 0, 1, 2, 3 and 4 from being lighted; the unactuated condition of relay 174 prevents lamp 9 from being lighted; the unactuated condition of relay 175 prevents lamps 8 and 6 from being lighted, and the unactuated condition of relay 176 prevents the lighting of lamp 5.

The setting up of any desired number by means of the lamps may be traced in a manner similar to that above described.

When the operator at 0' observes the lighting of the number indicating lamps, she releases the key whose springs are indicated at 133, 141 and 142, and the trunk is connected through springs 133 and 141 to the left-hand winding of repeating coil 134. The opening of the contact controlled by spring 142 results in the deenergization of relay 169, whereupon circuit is completed from grounded battery, winding of stepping magnet 157, side-switch wiper 158 in its 17th position, to ground through the armature and back contact of relay 169. The step-by-step switch makes one step into its normal position, causing the extinguishing of the lamps by the removal of ground from conductor 172. The step-by-step switch, as shown in the drawing, shows the wipers arranged to be swung over an arc of the circle, but for use with the circuit arrangement shown, it is to be understood that they would form a complete circle so that on leaving position 17, they will arrive in position 1.

We will now refer to that point of the operation where the impulse sending switch left position 16. On arriving in position 17, a circuit is completed from ground, impulse sending switch contact 177, sender sequence

switch contact 178, winding of power magnet 105 of the sender sequence switch, to grounded battery. The sender sequence switch moves out of position 5 into position 1 under the control of its normal spring 106. The impulse sending switch continues into position 1 where it comes to rest, since its normal spring 179 is now open and ground has been removed from sender sequence switch contact 144 by the operation of this switch.

When the sender sequence switch leaves position 5, a circuit is completed from ground, sender sequence switch contact 180, conductor 181, connecting cord sequence switch contact 182, winding of power magnet 100 of the connecting cord sequence switch, to grounded battery. The connecting cord sequence switch then moves from position 11 into position 16 under the control of its normal spring 102. In position 16 the talking strands of the cord shown at 0 are connected to the brushes 131 and 150 through connecting cord sequence switch contacts 187 and 191.

When the operator at 0' observes the lighting of the number indicating lamps, she inserts a plug 183 into jack 184 in which the wanted line terminates. Upon the completion of this operation, assuming that the line was idle, a circuit is completed for relay 139 from grounded battery, lamp 137, relay 139, sleeve of plug 183, sleeve contact of jack 184, and the winding of cut-off relay 185, to ground. Relays 139 and 185 are energized, relay 185 removing the control of the line signal from the called subscriber in the well-known manner. Relay 139 at its upper armature and front contact connects the upper talking conductor of the connecting cord to the tip conductor of plug 183. At its lower armature and front contact relay 139 completes a locking circuit for itself, from grounded battery, resistance 186, lower armature and front contact of relay 139, armature and front contact of relay 135, conductor 138, winding of relay 139, sleeve of plug 183, sleeve contact of jack 184, and the winding of cut-off relay 185, to ground. Since coil 186 is of comparatively low resistance, it shunts out lamp 137. Relay 135 is held energized at this time over a path from grounded battery, winding of relay 135, upper left-hand winding of repeating coil 134, lower contact of key spring 133, upper trunk conductor, terminal 132, brush 131, connecting cord sequence switch contact 187, and the upper right-hand winding of repeating coil 188, to ground.

The insertion of plug 183 into jack 184 and the subsequent response of the called subscriber, completes a circuit for supervisory relay 189 over the called subscriber's line in the usual manner. The operation of relay 189 completed a circuit for a super-

visory relay 190 over a circuit from ground-
ed battery, lower right-hand winding of re-
peating coil 188, winding of supervisory re-
lay 190, connecting cord sequence switch
5 contact 191, brush 150, terminal 151, lower
trunk conductor, upper contact of key spring
141, lower left-hand winding of repeating
coil 134, impedance coil 192, to ground
through the armature and front contact of
10 relay 189. The connection is now complete
and the subscribers may converse.

At the conclusion of the conversation,
after both parties have replaced their re-
ceivers, relay 189 will be deenergized, due
15 to the hanging up of his receiver by the
called party. This deenergization of relay
189 results in the deenergization of supervi-
sory relay 190. The hanging up of the
20 calling party's receiver results in the de-
energization of relay 193. The lighting of
the well-known supervisory lamps (not
shown) at the operator's position indicated
at 0, informs the operator that connection
25 is no longer desired and she removes plug 4
from jack 5, whereupon relay 7 is deener-
gized. The deenergization of relay 7 com-
pletes a circuit from ground, armature and
back contact of relay 7, connecting cord se-
quence switch contact 194, winding of power
30 magnet 100, to grounded battery, for mov-
ing the connecting cord sequence switch out
of position 16 and into position 18.

In position 18 of the connecting cord se-
quence switch, a circuit is completed from
35 grounded battery, winding of power magnet
195, connecting cord sequence switch con-
tact 196, to ground. Brush set 122 is re-
turned to normal position under the control
of a constantly rotating roller 197. When
40 brush 125 engages segment 198 a circuit is
completed from ground, brush 125, segment
198, connecting cord sequence switch contact
199, and the winding of power magnet 100,
to grounded battery, for moving the con-
45 necting cord sequence switch out of position
18 and into position 1. As soon as brush
set 122 moved off the terminals of the trunk
over which the connection is established,
the circuit of relay 135 is broken and the
50 shunt circuit about lamp 137 is removed.
The resultant lighting of lamp 137 informs
the operator at 0' and she removes plug 183
from jack 184. The apparatus has now all
been restored to normal and is ready for
55 reoperation.

Referring to that point of the operation
at which the operator at 0' inserted plug
183 into jack 184, it will be noted that if
the called line is busy, the operator will
60 receive a click in the receiver indicated at
200, due to the presence of potential on the
sleeve conductor of jack 184. This potential
will be supplied from grounded battery,
either through lamp 137 or through resist-
65 ance 186, and when the tip of plug 183 en-

gages the sleeve conductor of jack 184, a
circuit will be completed from grounded bat-
tery, tip of plug 107, upper armature and
back contact of relay 105, back contact of
relay 139, to ground through the receiver 70
indicated at 200, thus causing a click in the
receiver to notify the operator that the de-
sired line is busy.

What is claimed is:

1. In a multi-office telephone exchange 75
system, calling and called lines, a final con-
necting operator's position, a trunk line,
means for extending a calling line to said
operator's position over said trunk line, an
indicating device for displaying the number 80
of a called line at said position, means to
simultaneously send impulses over both sides
of said trunk, a step-by-step switch operated
by impulses over one side of said trunk,
and a combination of locking relays to con-
85 trol said indicating device, desired ones of
said relays being energized by impulses over
the other side of said trunk.

2. In a multi-office telephone exchange 90
system, calling and called lines, a final con-
necting operator's position, a trunk line,
means for extending a calling line to said
operator's position over said trunk line, an
indicating device for displaying the num-
95 ber of the called line at said position, means
to simultaneously send impulses over both
sides of said trunk, a step-by-step switch
operated by impulses over one side of said
trunk, and a combination of locking relays
100 to control said indicating device, desired
ones of said relays being energized in corre-
sponding positions of said switch by im-
pulses over the other side of said trunk.

3. In a multi-office telephone exchange 105
system, calling and called lines, a final con-
necting operator's position, a trunk line,
means for extending a calling line to said
operator's position over said trunk line, an
indicating device for displaying the number
110 of the called line at said position, means to
simultaneously send impulses over both sides
of said trunk, a step-by-step switch operated
by impulses over one side of said trunk, a
set of fixed contacts arranged for engage-
115 ment by a wiper of said switch, and a lock-
ing relay associated with each of said fixed
contacts, said relays being arranged to be
energized by impulses over the other side of
said trunk.

4. In a multi-office telephone exchange 120
system, calling and called lines, an "A"
operator's position, a "B" operator's posi-
tion, a trunk line, means for extending a
calling line to said "B" operator's position
over said trunk line, an indicating device 125
for displaying the number of the called line
at said "B" operator's position, a key set
at said "A" operator's position, means to
simultaneously send impulses over both
sides of said trunk, a step-by-step switch op- 130

erated by impulses over one side of said trunk, and a combination of locking relays to control said indicating device, desired ones of said relays being energized by impulses over the other side of said trunk in accordance with the setting of said key set.

5 5. In a multi-office telephone exchange system, calling and called lines, an "A" operator's position, a key set thereat, a "B" operator's position, a trunk line, means to extend a calling line to said "B" operator's position over said trunk line, an indicating device for displaying the number of the called line at said "B" operator's position, 10 a multi-position sending switch at said "A" operator's position, means including said switch to simultaneously send impulses over both sides of said trunk, a step-by-step switch operated by impulses over one side of 15 said trunk, and a combination of relays to control said indicating device, desired ones of said relays being energized by impulses over the other side of said trunk in accordance with the setting of said key set.

20 25 6. In a multi-office telephone exchange system, calling and called lines, an "A" operator's position, a "B" operator's position, a trunk line, means to extend a calling line to said "B" operator's position over said trunk line, an indicating device for displaying the number of the called line at said "B" operator's position, a multi-position sending switch at said "A" operator's position, said switch being arranged to move 30 35 through its cycle of positions and return to normal without stopping when moved out of normal, means including said switch to simultaneously send impulses over both sides of said trunk, a step-by-step switch operated by impulses over one side of said trunk, and a combination of relays to control said

indicating device, desired ones of said relays being energized by impulses over the other side of said trunk in accordance with the setting of said key set.

45

7. In a telephone system, two conductors, a signaling device, means for simultaneously sending impulses over both of said conductors, a step-by-step switch operated by impulses over one of said conductors, and a combination of locking relays arranged to be operated by impulses over the other conductor to selectively operate said signaling device.

50

8. In a telephone system, two conductors, a signaling device, means for simultaneously sending impulses over both of said conductors, a step-by-step switch operated by impulses over one of said conductors, a set of fixed contacts arranged for engagement by a wiper of said switch, and a relay associated with each of said fixed contacts, said relays being arranged to be operated by impulses over the other conductor to selectively operate said signaling device.
